UNITED STATES PATENT OFFICE.

MAX P. HERMANN, OF PHILADELPHIA, PENNSYLVANIA.

RULING-PEN.

1,340,895.

Specification of Letters Patent. Patented May 25, 1920.

Application filed June 26, 1919. Serial No. 306,904.

To all whom it may concern:

Be it known that I, MAX P. HERMANN, a citizen of the United States, residing at Philadelphia, in the county of Philadelphia and State of Pennsylvania, have invented certain new and useful Improvements in Ruling-Pens, of which the following is a specification.

One object of my invention is to provide 10 an improved ruling pen, such for example as a ruling pen used by draftsmen, in which the blades or nibs can be quickly and easily made from sheet metal.

Another object is to so make my improved 15 ruling pen that it will include a gage whereby the nibs or blades can be accurately set any desired distance apart for ruling lines of various widths so that a draftsman, without trial of the pen upon paper, can determine the width of the line which the pen 20 will rule and thereby save considerable time in his work.

Another object is to so make the parts of 25 my improved pen that they can be easily taken apart for cleaning purposes and can be readily assembled.

A further object is to so make the parts 30 of my improved pen that the nibs or blades can be easily adjusted by the movement of a member conveniently located so that it can be easily operated by the same hand in which the pen is held.

These objects, and other advantageous ends which will be described hereinafter, I 35 attain in the following manner, reference being had to the accompanying drawings in which—

Figure 1 is a side elevation of a ruling pen constructed in accordance with my invention,

Fig. 2 is a top plan view of Fig. 1,

Fig. 3 is a sectional elevation taken on the line 3—3 of Fig. 2,

Fig. 4 shows a top plan view of one of the 45 blades or nibs of my improved pen, illustrating how the same is stamped or cut from a single piece of sheet metal and afterward bent into the form shown in Figs. 1 to 3 inclusive,

Fig. 5 is a plan view of the other blade 50 or nib of my improved pen showing the same as stamped from a piece of sheet metal,

Fig. 6 is a plan view of an actuating lever which forms a part of my invention,

Fig. 7 is a transverse section taken on the line 7—7 of Fig. 6,

Fig. 8 is a side elevation of another form of pen made in accordance with my invention,

Fig. 9 is a top plan view of Fig. 8,

Fig. 10 is a sectional elevation taken on the line 10—10 of Fig. 9,

Fig. 11 is an enlarged transverse section taken on the line 11—11 of Fig. 10,

Fig. 12 is a side elevation of another form of my invention showing the ordinary manner of adjusting the blades or nibs but including certain features of my invention, and

Fig. 13 is a top plan view of Fig. 12.

Referring to Figs. 1 to 7 inclusive, 14 represents one of the blades or nibs of my improved pen which may be termed the main blade and which is made by cutting or stamping a piece of flat sheet steel of the shape shown in Fig. 4. After cutting the same from the flat sheet of steel, the laterally extending portions 15 are bent substantially at right angles to the main portion 16. A channel 17 is thus formed between the portions 15 and the central portion 16. In this channel I secure a block 18 of metal by brazing or soldering and insert a screw 19 therethrough as clearly shown in Fig. 3. Said block has a screw threaded stem 20 which is screwed into a handle 21. The screw 19 has an enlarged upper portion 22 which provides a shoulder 23 for holding the upper blade 24 between the portion 22 and the top of the block 18. A cap 25 is internally screw threaded and fits upon the screw portion 22, said cap having its upper face graduated, as shown at 26 in Fig. 2. A lever 27 has trunnions 28 projecting therefrom, said trunnions being adapted to be inserted under rearwardly extending hooks 29 which are a part of the portions 15. The rear end portion 30 of the lever 27 rests on a central pivot projection 31 on the top of the cap 25. The opposite end portion 32 of the lever 27 bears against the top surface of the upper blade 24 at a position forward of the trunnions 28, said latter plate and lever being positioned between the portions 15, as clearly shown in Figs. 1, 2 and 3. The upper blade 24 is reduced in width as shown at 33 to provide shoulders 34, said shoulders being adapted to engage in front of the rearwardly curved

105 110

edges 35 of lugs 36. The blade 24 is curved to include a hump 37, and it is upon this hump that the end portion 32 of the lever 27 bears, as clearly shown in Figs. 1 and 3.

5 The portion 30 of the lever 27 has a pointed end 38 which is adapted to register with the graduations 26 on the top of the cap 25. It will thus be noted that by turning the cap so that it rises upon the screw 22, the end portion 32 of the lever will move the upper nib or blade 24 toward the lower main blade 14 so as to vary the space between the nibs at their extreme forward ends, and the distance apart of said forward ends can be determined by the relative position between the pointed end 38 of the lever 27 and the graduations 26 on the cap 25. It will thus be understood that the forward ends of the upper and lower blades are normally apart, due to the resiliency of the upper blade and also its mounting. Therefore, when the cap 25 is turned downwardly upon the screw 22 the rear end of the lever 27 will move downwardly and the resiliency 20 of the blade 24 will cause the latter to move away from the blade 14, as is obvious from the construction as illustrated and above described.

Referring to Figs. 8 to 11 inclusive, instead of providing an upwardly extending screw and cap, such as shown at 22 and 25, I have illustrated a smooth cylindrical portion 39 which is interposed between the block 18^a and the screw threaded stem 20^a 35 to which the handle 21^a is attached. The cylindrical portion 39 forms a bearing for a sleeve 40 which has graduations 41 on its outer peripheral surface adjacent its forward end. The sleeve 40 has a pin 42 which 40 projects into a cam 43 which is mounted on the cylindrical portion 39 so that when the handle 21^a is turned into its proper position as shown in Figs. 8, 9 and 10, the cam 43 can be rotated by rotating the sleeve 40.

45 A screw 19^a has a smooth end 44 which projects through a slot 45 in a lever 27^a. The rear end 38^a of the lever 27^a rests against the surface 46 of the cam 43. The sleeve 40 has a recess 47 directly adjacent the rear 50 of the cam 43. In all other respects the construction is similar to that described in connection with Figs. 1 to 7 inclusive and I have therefore given similar reference characters to corresponding parts. It will be noted that to operate the blades of the form of my invention shown in Figs. 8 to 11 inclusive that it is merely necessary to rotate the sleeve 40 upon the cylindrical portion 39 and the cam 43 will operate the lever 27^a in 55 the same manner as the cap 25, above described, operates the lever 27. The recess 47 is so placed that when the low part of the cam 43 is turned into register therewith that it is an easy matter to remove the lever 27^a 60 and the parts can be removed by pressing

the lever 27^a downwardly to free the trunnions 28 from the hooks 29. The lever 27^a can then be slid rearwardly and entirely removed, as can also the handle 21^a, sleeve 40 and cam 43. The blades can then be thoroughly cleaned or sharpened if desired. 70

In Figs. 12 and 13 I have illustrated a pen in which the blades 47^a and 48 are made similar to those above described with the exception that the hooks 29 are omitted. In 75 this form of my invention the lower blade 47^a includes a screw threaded post 49 having an adjusting screw 50 mounted thereon for the purpose of directly compressing the blade 48 toward the blade 47^a. A block 51 80 is interposed within the channel 52 and a screw 53 secures the blade 48 to the block 51. The block has a screw threaded stem 54 which screws into a handle 55. The blades of this form of my invention are produced 85 of sheet metal and the channel 52 is provided by bending in the same manner as described in connection with the parts 15 and 16 of the form of my invention shown in Figs. 1 to 7 inclusive. 90

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims. 95

Having thus described my invention, what 100 I claim as new and desire to secure by Letters Patent is:—

1. A pen including a blade having a channel formed by bent-up portions providing trunnion bearings; a second blade having a 105 part located within said channel; a lever having trunnions swingably engaging said trunnion bearings; and means for adjustably moving said lever whereby the latter engages said second mentioned blade and moves it 110 toward said first blade; substantially as described.

2. A pen including a blade having a channel formed by bent-up portions provided with hooks to form a fulcrum; a second blade having a part normally spaced from said first blade; a lever having portions swingably engaging said fulcrum and bearing against said second mentioned blade; and adjustable means for moving said lever 115 whereby the latter engages said second mentioned blade and moves it toward said first blade; substantially as described.

3. A pen including a blade having portions bent to provide a channel and including hooks formed on the sides thereof to serve as a bearing; a second blade secured relatively to said first blade; a lever having portions swingably engaging said bearing; and adjustable means for swinging said le- 125 130

ver on its bearing to cause the lever to move said second blade toward said first blade; substantially as described.

4. A pen including a blade having bent-up side portions provided with rearwardly extending hooks to form a bearing; a second blade secured relatively to said first blade; a swingable lever having trunnions for engagement under said hooks as a bearing and 10 having a portion engaging on said second blade; and adjustable actuating means for swinging said lever on its bearing whereby the blades are moved together by the action of the lever; substantially as described.
- 15 5. A pen including a blade having bent-up side portions provided with rearwardly extending hooks to form a bearing; a second blade secured relatively to said first blade; a swingable lever having trunnions for engagement under said hooks as a bearing and 20 having a portion engaging on said second blade; and adjustable actuating means for swinging said lever on its bearing whereby the blades are moved together by the action 25 of the lever, said second blade having shoulders thereon for engagement with parts of said bent portions of the first blade; substantially as described.

6. A pen including a blade having bent-up side portions provided with rearwardly extending hooks forming a bearing; a second

blade secured relatively to said first blade; a swingable lever having trunnions for engagement under said hooks as a bearing and having a portion engaging said second blade; 35 and adjustable actuating means for swinging said lever on its bearing whereby the blades are moved together by the action of the lever, said second blade including a hump against which said lever bears; substantially as described.

7. A pen including a blade having a channel formed by bent-up portions providing trunnion bearings; a second blade having a part located within said channel; a lever 45 having trunnions swingably engaging said trunnion bearings; and means for adjustably moving said lever whereby the latter engages said second mentioned blade and moves it toward said first blade, said moving means 50 having graduations thereon with which a portion of the lever registers whereby the extent of movement of the lever can be determined; substantially as described.

In testimony whereof I have signed my 55 name to this specification in the presence of two subscribing witnesses.

MAX P. HERMANN.
